(57) **CLAIM**

The ornamental design for a phone stand with speaker and lamp, as shown and described.

DESCRIPTION

FIG. 1 is a front, right, and top perspective view of a first embodiment of a phone stand with speaker and lamp showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a rear, left, and bottom perspective view thereof, where the phone stand with speaker and lamp is in a folded state;

FIG. 10 is a front, right, and top perspective view thereof, where the phone stand is lowered to another position;

FIG. 11 is a front, right, and top perspective view thereof, where the kickstands for supporting a mobile phone are in a folded state;

FIG. 12 is a front, right, and top perspective view thereof, where a mobile phone is placed on the stand;

FIG. 13 is a front, right, and top perspective view of a second embodiment of a phone stand with speaker and lamp showing my new design;

FIG. 14 is a rear, left, and bottom perspective view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom plan view thereof;

FIG. 21 is a rear, left, and bottom perspective view thereof, where the phone stand with speaker and lamp is in a folded state;

FIG. 22 is a front, right, and top perspective view thereof, where the phone stand is lowered to another position;

FIG. 23 is a front, right, and top perspective view thereof, where the kickstands for supporting a mobile phone are in a folded state; and,

FIG. 24 is a front, right, and top perspective view thereof, where a mobile phone is placed on the stand.

The broken lines in the drawings depict portions of the phone stand with speaker and lamp that form no part of the claimed design. The remaining broken lines depict a mobile phone shown in FIG. 12 and FIG. 24, which is as an environmental subject matter and forms no part of the claimed design.
